EARTH BORING SAMPLER

Filed May 31, 1928

J. Steigh & E. F. Choate. Inventor

By A. F. Andrews Jr. Attorney

UNITED STATES PATENT OFFICE

JACOB STEIGH AND EARL F. CHOATE, OF LONG BEACH, CALIFORNIA

EARTH-BORING SAMPLER

Application filed May 31, 1928. Serial No. 281,773.

This invention relates to an earth boring sampler.

The present invention constitutes an improvement of the construction disclosed in 5 Letters Patent of the United States issued to us on January 26, 1926, for an improved earth boring sampler, No. 1,570,647.

The aim of the present invention is to provide a construction which is generally improved over that of our patent aforesaid, and 10 particularly provide a construction which will reduce the liability of the sampling tube to rotation to the minimum accordingly preventing damage to the core.

15 Another object is to provide the improved construction with novel means for venting the tube and supplying the fluid to the cutter.

Additional objects and advantages will become apparent from a consideration of the 20 description following taken in connection with accompanying drawings illustrating an operative embodiment, and wherein:

Figure 1 is a view showing the tube and associated parts of a drilling rig,

25 Figure 2 is a sectional view taken on the line 2—2 of Figure 1, and

Figure 3 is a sectional view taken on the line 3—3 of Figure 1.

Referring specifically to the drawings, the 30 sampling tube is shown at 10 and consists of a tube open at its bottom and closed at its upper end or top side from a vent valve as at 11, which is normally closed and may be of the construction disclosed at 4 in our patent 35 aforesaid.

Screw threaded to the tube 10 at 10^a and rising therefrom is a dome 12 of reduced diameter, into the interior of which the valve 11 extends and with which it communicates.

40 Valve 11 is carried by a disk 11^a screw threaded at 11^b to the interior of dome 12. Said dome has vent ports 11' and laterally extending flanges at 13 which are engaged by flanges 14 and 14^a of a channeled ring 15 fastened as 45 at 16 within a casing 17. Flange 14^a is removable in order that the parts may be assembled, and it is held in place by bolts 14^b.

The casing 17 is adapted for rotation relative to the tube 10 and the latter is adapted 50 to remain stationary as far as practical.

Such relative movement is rendered frictionless as far as practical by the provision of ball bearings as at 18 between the flanges 13 and 14.

At the lower end, the casing 17 is provided 55 with a suitable cutter or cutting teeth 19.

At the upper end, an operating rod 20 may be detachably screwed as at 21. The operating rod is adapted to be turned from above in the usual manner to thereby impart 60 rotation to the casing.

The rod 20 and casing 17 rotate about a water supply pipe 22 which extends axially thereof and through the top of the dome and into the latter, having outlet branches 23 fastened at 24 on the wall of the dome and adapted to discharge exteriorly of the dome and into the interior of the casing. The water discharged into the interior of the casing is adapted to leave or escape downwardly between the sampling tube 10 and casing 17 to the cutters 19 and thence upwardly exteriorly of the casing to remove cuttings as usual.

Provided in the lower end of the sampling tube are sample-retaining fingers 25 which are of resilient metal and have their lower portions 26 welded or brazed within grooves 27 in the inner wall of such tube.

Under the action of the sample, the fingers 25 are displaced outwardly and completely into such grooves or slots 27 so that the sample may enter the tube and the fingers will not so interfere with the sample as to cause it to in turn cause the sampling tube to rotate with the casing. In other words, the structure is such that the sampling tube remains stationary practically all of the time and is not rotated when engaged by the sample so that damage to the core is accordingly prevented.

It will be understood that in the usual manner, as the cutter 19 is driven into the earth, it cuts out a core or sample which enters 95 the tube 10 and can be removed therefrom for sampling or testing purposes.

Various changes may be resorted to provided they fall within the spirit and scope 100 of the invention.

We claim as our invention:—

An apparatus of the class described comprising a casing, a channeled ring therein providing flanges, a sampling tube having a dome thereon provided with flanges engaged by the first mentioned flanges and on which the latter are adapted to rotate, a water supply pipe extending axially of the casing and through the dome, a vent port in said dome, and a vent valve in said tube opening into the dome.

In testimony whereof we affix our signatures.

JACOB STEIGH.
EARL F. CHOATE.
